INVENTOR

George J. Leber
by Albert Edgmont
NO ATTORNEY

UNITED STATES PATENT OFFICE.

GEORGE J. LEEBER, OF CLEVELAND, OHIO.

HOSE REEL.

Application filed July 14, 1921. Serial No. 484,717.

To all whom it may concern:

Be it known that I, GEORGE J. LEEBER, a citizen of the United States of America, residing at Cleveland, in the county of Cuyahoga and State of Ohio, have invented certain new and useful Improvements in Hose Reels; and I hereby declare the following to be a full, clear, and exact description of the invention, such as will enable others skilled in the art to which it pertains to make and use the same.

This invention relates to certain new and useful improvements in reels, and particularly to a reel for winding up and storing garden hose.

One object of this invention is to provide a reel of this character which can be easily operated and on which the hose can be tightly coiled without any manual manipulation of the hose itself.

A further object of my invention is to provide a reel of the character indicated which will be very strong in construction, light in weight and very compact.

With these objects in view and with the intention of securing other advantages which will hereinafter appear, my invention consists in the features of construction and combination of parts hereinafter described in the specification, particularly pointed out in the claims and illustrated in the drawings.

Referring to the accompanying drawings, Fig. I is a view in elevation of a reel embodying my invention. Fig. II is a section on line A—A Fig. I, with the addition of a series of dotted circles to represent the position the coils of the hose would assume on the reel.

By referring to the drawings, it will be seen that my improved reel comprises a central body or hub portion 10, comprising preferably a substantially or approximately flat plate of sheet metal or other sheet material of the desired thickness, the same being located substantially at right angles to the axis of the reel. In the present instance the central body portion is circular in form, altho the same may be constructed in any other desired form, such as square or hexagonal. In production the body portion may be preferably formed from a stamping. On each side of the body or hub portion 10, adjacent to its free edge is mounted a series of radially projecting arms or spokes 11, and each carrier arm on one side is arranged to

register with an arm on the other side. The carrier arms or spokes of each pair of arms in the present form are secured to each other and to the body member 10, as by means of rivets 12, altho the same may be secured to the central body in any other preferred manner, as by spot-welding. The companion arms of the several pairs, where they are secured to the body member 10, and for a short distance beyond the circumference of the body member, extend parallelly with each other and then the said arms diverge forming a V-shaped space or opening. Or in other words, each pair of arms may be said to form a V-shaped bracket member. These arms or spokes in construction are preferably flat in the form of metallic straps and as a result may be readily attached or secured to the flat hub portion and bent once upon themselves to embrace the wire rims 14.

On the outer ends of each series of carrier arms or spokes is mounted a rim 14. These rims are preferably formed of heavy wire butt-welded into continuous solid rims 80 and are mounted or placed over the ends of the spokes 11. Thereupon the spokes are bent over the wire rims forming eyes 13 embracing the same, thereby resulting in the provision of a rigid and durable reel structure. On the body portion is mounted a short radially projecting arm 15, which is provided with an annular head portion or eye 16 adapted to receive and retain or anchor the nozzle of the hose. It will be noted in the present embodiment that the eye 16 for anchoring the hose is spaced from the central body portion so as to be substantially in annular or circumferential alinement with the several apexes of the V-shaped openings formed by the spokes 11.

The operation of my reel will be readily understood. When it is desired to wind or coil the hose on the reel the nozzle of the hose is inserted through the annular head 13 100 on the arm, 15. The reel is then rolled over the ground with the rims of the reel straddling the hose. The reel is caused to travel lengthwise of the hose and as the reel moves over the ground the hose is picked up from the ground and is coiled around the central portion of the reel and supported between the series of arms on one side of the body member and the series of arms on the other side of the body member.

The advantages of my reel will be readily appreciated. When operating the general

type of garden hose reels now on the market, before starting to coil the hose it is necessary to lay the hose out in a practically straight line or else every inch of the hose, generally fouled with sand or dirt, must be passed through the hands in order to adjust it on the drum of the reel. Also at the same time the carriage of the reel must be shifted back, forth and sidewise and as the ground 10 is always soft after the sprinkling, this procedure causes a disfigurement of the lawn through the tearing up of the sod. Owing to the fact that my reel is of very light weight and the supporting rims are comparatively large in circumference the reel 15 will not dig into or disturb the sod. Also my reel can be caused to travel or roll in one direction and then with a slight motion of the hand the reel can be caused to travel 20 at an angle to its original path or in a directly opposite direction. This makes it easy to take up the hose even when it is spread in a zig-zag course over the lawn. So long as the rims are caused to straddle the 25 hose, the hose need not be touched by the hands, as the hose will be picked up and coiled between the opposing arms without any manual assistance.

Owing to the V-shaped opening between 30 the arms on the opposite sides of the body member, the hose will be coiled very regularly and in compact layers. When the first coil is rolled on it will of course settle into the apex of the V-shaped opening, the 35 next coil will rest on the first coil, but the succeeding coil will move down the inclined sides of the arms and will wedge against the second coil. In forming the third layer, the first two coils will be rolled on and then 40 the next coil will move down the inclined sides of the arms assuming its proper place and wedging the other coils into their proper places. In this way the whole roll of hose will be built up evenly and compactly 45 on the reel.

After the hose has been wound on the reel, the reel can be trundled over the ground as a child rolls a hoop or the reel and hose can be picked up bodily and carried without difficulty to its place of storage. As the reel 50 is very compact, when not in use, the reel can be hung from a wall by causing one of the rims to engage with a hook or other support. This feature renders the reel very suitable for garage use where space is generally quite limited.

Although I have described my invention in a preferred form thereof, it is to be understood that I do not limit myself to the 60 details or construction herein shown and described, but may make such changes as are embraced within the scope of the claims.

What I claim is:—

1. A hose reel comprising a body portion 65 consisting of a metallic plate, a series of

arms secured to each side of said plate near its circumference and equally spaced circumferentially of said plate, each arm in a series on one side of the plate being arranged to register with an arm of the series on the other side of the plate, the arms in each series being inclined away from the arms in the other series and a rim mounted on the free ends of the arms of each series. 70

2. A hose reel comprising a body member 75 formed from a flat plate of sheet metal, V-shaped bracket members secured to and projecting radially beyond the circumference of said body member and rims mounted on the free ends of the bracket arms at 80 each side of the body member.

3. A hose reel comprising a sheet metal body portion, arms secured at the inner ends thereof to said body portion and extending radially therefrom, said arms being arranged in pairs and the arms forming each pair being oppositely inclined, a rim connecting together all the arms on one side of the plate, and a rim connecting together all the arms on the other side of the plate, said 85 arms at their outer ends being bent upon themselves to embrace said rims. 90

4. As an article of manufacture, a hose reel comprising a pair of spaced rims, a plurality of inclinedly arranged spokes engaging said rims, and a hub plate secured to said spokes in a plane substantially parallel with said rims. 95

5. As an article of manufacture, a hose reel comprising in combination a central hub plate, a pair of rims laterally and radially spaced therefrom and lying in planes substantially parallel thereto, and a plurality of convergingly arranged spokes, each thereof rigidly attached at one end to the hub plate and bent upon itself at the opposite end to embrace a rim. 100 105

6. As an article of manufacture, a hose reel comprising in combination a central hub plate, a pair of rims laterally spaced therefrom, and a plurality of convergingly arranged spokes embracing said rims, said hub plate having flat faces permitting attachment of the spokes thereto. 110

7. As an article of manufacture, a hose reel including in combination a hub formed of sheet material, rims spaced laterally therefrom and located in planes substantially parallel thereto, and a plurality of spokes attached to said hub and engaging 115 120 said rims.

8. A hose reel comprising a body member formed from a substantially flat plate of sheet metal, V-shaped bracket members secured to and projecting radially beyond the circumference of said body member and rims mounted on the free ends of the bracket arms at each side of the body member, and a hose retaining member rigidly secured to 125 said body member in spaced relation thereto. 130

9. A hose reel comprising a sheet metal hub plate, V-shaped bracket members secured to and projecting radially beyond the circumference of said plate and rims mounted on the free ends of the bracket arms at each side of the plate, and a nozzle-receiving member rigidly secured to said body member in spaced relation thereto and comprising an eye-formed portion located substantially in annular alinement with the several vertices of said bracket.

10. As an article of manufacture a hose reel comprising a hub having substantially flat-sided portions located radially of the axis of the hub, rims laterally spaced from said hub, and spokes connected to said hub portions and rims.

11. As an article of manufacture, a hose reel constructed to receive a plurality of coils of hose or the like and including a pair of spaced rims, a plurality of spokes extending radially therefrom, and a central body member located in a plane transverse of the axis of said reel, said body member having flat faces for attachment to said spokes.

In testimony whereof, I sign the foregoing specification, in the presence of two witnesses.

GEORGE J. LEBER.
